UNITED STATES PATENT OFFICE

2,394,323

CONTAINER HOLDER

Edward Menke, Cincinnati, Ohio

Application July 11, 1944, Serial No. 544,409

3 Claims. (Cl. 81—3.32)

My invention relates to container holders and particularly to a novel container holder adapted to receive and hold containers of different diameters.

It is an object of my invention to provide a container holder which will be readily adjustable to receive jars or cans of different sizes and which will be provided with means by which the containers may be securely held during such operations as require the container to be held securely while a screw top lid is applied or removed. In connection with cans, the holder may be used for holding the can during the use of a can opener to remove the can top.

It is an object of my invention to provide a device for assistance to women during vegetable and fruit canning operations. Such operations ordinarily require the jar with the screw top lid loosely applied thereon to be inserted in boiling water. When the jar is removed from the boiling water, it is necessary to tighten down securely the screw top lid to prevent the introduction of air during the time when the contents of the jar cool. A towel may readily be used for tightening the lid, but it is extremely difficult to hold the jar body during the time the lid is being tightened. Such jars are of different shapes, some being square and some round, and their size is such that the hand cannot readily grasp them and hold them immovable while the lid is being tightened.

It is broadly my idea to provide a device which can be readily operated to hold any size jar or can in fixed immovable position without the necessity of the housewife holding the jar by means of a cloth or towel. The above objects and other objects to which reference will be made in the ensuing description, I accomplish by that certain construction of which I have illustrated a preferred embodiment.

In the drawing

Figure 1 is a top plan view of the container holder.

Figure 2 is a front elevation of the same.

Figure 3 is a side elevation with portions broken away to show a preferred ratchet type lock used during adjustment of the length of the holding band or belt.

Referring to the drawing, I have indicated at 1 in Figure 1 a supporting base which may be, as shown, a flat, rectangular shaped piece of wood.

Firmly secured to the base, there is an upright wall 2, which may also be formed from a rectangular piece of wood, and this wall has on

it an abutment 3 extending up in substantially vertical position.

I have shown at 4 a container, the particular container illustrated being a two-quart jar having a screw top lid 5.

It will be observed that in holding the container, it is positioned on the supporting base with one side contacting the abutment member 3. The upper wall of the abutment member is ordinarily contoured as indicated at 5a in Figure 1. Whether the container is round or square in horizontal section, an arcuate shaped abutment, as indicated at 5, will hold the container in position.

15 Extending through slots 6 in the member 2, there is illustrated the flexible band or belt 7. The belt extends out over the supporting base in position to form an enclosure for the container.

20 In order to provide an adjustment by which the length of the belt may be predetermined, one end of the belt 8 is secured to a reel 9 mounted on a vertical pivot 10 secured in the base.

The reel has ratchet teeth 11 arranged in a 25 circular formation at its top and these teeth are engaged by a pawl 12. The pawl 12 is mounted on an arm 13 pivoted at 14.

It will be obvious that the length of the belt may be adjusted by turning the reel by means 30 of a knurled hand wheel 15. Figure 1 suggests a range of different dimensions for the flexible band to accommodate containers of different sizes.

In order to adjust the length of the band from 35 a smaller to a larger enclosure area, I have provided a guide 16 which prevents the flexible band from buckling during counterclockwise rotation of the hand wheel 15.

The other end of the belt is secured to a spindle 17 mounted on a vertical pivot 18 and a handle 19, which may readily be grasped by one hand, is secured to the spindle 17, so that when a container is in position on the base, by pulling the handle 19 toward the fixed arm 20, enough 45 take-up will occur in the belt to hold the container in firm, rigid position.

A spring 21 may be provided so as always to return the manually adjustable handle 19 to inoperative position.

50 The operation of the device is exceedingly simple. First, the length of the belt extending out over the base is adjusted by means of turning the hand wheel 15. The belt is adjusted to such a size as will receive loosely the container, and after the container is in position, the belt is

tightened by means of the handle 19. This can readily be done with the left hand, which leaves the right hand free to tighten or release the lid of the container.

In connection with cans to be opened, the same operation takes place. The left hand holds the container in position, and the right hand can be used for operating the can opener. If the person using the holder is left-handed, the handle 19 can be held with the right hand, and the lid tightened or the can opener used with the left hand.

I have shown a construction made from wood which is the simplest form of construction available, but it should be understood that an equivalent combination of devices may be made from metal, plastic, or combinations of other materials. Also, the size and shape of the various parts may be modified to suit the particular requirements of the particular types of containers for which the device is adapted.

Having thus described my invention, what I claim as new and desire to secure by Letters Patent is:

1. In combination with a base, an upright support having a substantially vertical abutment portion, a flexible band extending out from said abutment portion and enclosing an area above said base, a reel to which one end of said flexible band is secured, means for rotating said reel to adjust the length of the band extending out from said abutment portion, means for locking the reel in predetermined positions, and manual means adjacent the other end of said band for taking up sufficiently on the end of the band re- 35

mote from the reel to retain firmly a container placed on said base in non-rotative position.

2. In combination with a base, an upright support having a substantially vertical abutment portion, a flexible band extending out from said abutment portion and enclosing an area above said base, a reel to which one end of said flexible band is secured, means for rotating said reel to adjust the length of the band extending out from said abutment portion, means for locking the reel in predetermined positions, manual means adjacent the other end of said band for taking up sufficiently on the end of the band remote from the reel to retain firmly a container placed on said base in non-rotative position, and a guide for preventing buckling of said band during adjustment thereof.

3. In combination with a base, an upright support having a substantially vertical abutment portion, a flexible band extending out from said abutment portion and enclosing an area above said base, a reel to which one end of said flexible band is secured, means for rotating said reel to adjust the length of the band extending out from said abutment portion, means for locking the reel in predetermined positions, and manual means adjacent the other end of said band for taking up sufficiently on the end of the band remote from the reel to retain firmly a container placed on said base in non-rotative position, said manual means comprising a member adapted to be grasped with one hand, and spring means for maintaining said manual means in inoperative position when not in use.

EDWARD MENKE.
